UNITED STATES PATENT OFFICE.

WILLIAM H. CALLAHAN, OF NEW YORK, N. Y.

DEVICE FOR CLEANING HOLLOW ARTICLES.

No. 878,768.

Specification of Letters Patent.

Patented Feb. 11, 1908.

Application filed June 13, 1906. Serial No. 321,459.

To all whom it may concern:

Be it known that I, WILLIAM H. CALLAHAN, a citizen of the United States, and a resident of the borough of Manhattan, city, 5 county, and State of New York, have invented certain new and useful Improvements in Devices for Cleaning Hollow Articles, of which the following is a specification, reference being had to the accompanying 10 drawings, which form a part thereof.

The objects of my invention are to provide a device which will clean the interior of bottles, or similar hollow articles, in a quick, efficient and sanitary manner, at the same 15 time preventing the abrading of the surface of the article to be cleaned.

A more important object is to provide a device which will easily, quickly and thoroughly clean bottles or like receptacles having small necks.

Referring to the drawings, Figure 1 is a perspective view of my device partly in section, illustrating the manner in which it is used in cleaning a bottle. Fig. 2 is a section 25 of the cleaner showing details of construction. Fig. 3 illustrates a modification which is intended for use with articles having large mouths, such as lamp chimneys. Fig. 4 is a cross section of the device taken at right angles to the longitudinal axis. Throughout 30 the drawings, like reference numerals refer to like parts.

My device consists essentially of a bag of fabric adapted to be suspended within the 35 receptacle and provided with means for causing the said fabric to impinge upon the inner surface of the walls of the article to be cleaned. It is obviously susceptible of various modifications without departing from 40 the spirit of my invention. I do not, therefore, wish to be understood as limiting myself to the particular form shown and described but desire to cover the invention broadly as pointed out in the claims.

45 Referring particularly to Figs. 1 and 2, 1 is a stopper of cork or other suitable material, and is preferably tapered as shown in order to adapt it for use with articles having mouths of different sizes. This stopper I 50 prefer to provide with a handle such as the wire loop 2 which will also serve as means for hanging up the articles. To the base of this stopper is secured a cord 3 which may be fastened to the stopper by extending the 55 wire forming the loop 2 therethrough, form-

ing its lower end into a hook 4 and securing the cord to the said hook. At suitable points upon this cord I string a plurality of beads 5, 5 &c. of glass or porcelain so that they may move freely upon the said cord. To retain these beads within certain desired limits, however, I provide stops 6 and 7 of felt or other suitable material, immovably fastened to the cord. Surrounding this cord and the beads is a bag 8 of some suitable fabric and the lower end of the cord is preferably secured to the lower end of the bag. The bag may be made of many different materials, but I have found in practice that Turkish toweling gives very satisfactory results. 60 The shape of this bag is capable of considerable variation, although I prefer to make it conical having its largest portion near the lower end. From this point it may be again tapered to a point. The bag may be fastened to the stopper in any desired manner, although I have shown it as secured to the end of the wire which projects below the stopper by wrapping wire or thread about 65 the bag and the said wire. 70

The mode of operation of my device is as follows: A small amount of water is placed within the article to be cleaned, and if desired some suitable washing powder is introduced, although I find that this is generally 85 unnecessary. The cleaner is then introduced into the article and in the case of a bottle the stopper pressed into the neck. The whole is then shaken for a few moments and the beads within the bag cause the 90 fabric to impinge upon the bottle with considerable force and will therefore clean the surface very satisfactorily. The cleaner is then removed and the article may be rinsed and dried. It will be found that the cleaner 95 will retain few impurities upon its surface, and that what few are retained can be easily removed either by rinsing or by washing.

To adapt the device for cleaning articles having large necks, such as lamp chimneys 100 for example, it is only necessary to replace the stopper by some larger article. In practice I have successfully used the form shown in Fig. 3 in which the plate 9 of moderately stiff felt is used in place of the stopper, the 105 remainder of the device being unchanged, the essential feature in this regard being the provision of a closure for the bottle or other like article, which closure may be a stopper (1) or a plate (9) as stated. 110

Having described my invention, what I claim is:

1. In a bottle cleaning device the combination of a stopper adapted to close the mouth of the article to be cleaned, a bag of fabric attached to base of said stopper, a cord having its upper end attached to said stopper and its lower end attached to the bottom of said bag, and a plurality of beads mounted upon said cord adapted to facilitate the introduction of said bag into said article and to cause it to impinge upon its inner surface when agitated.
2. In a bottle cleaning device the combination of a stopper provided with a handle, a fabric bag attached to the bottom of said stopper, a cord within said bag having one

end fastened to the stopper and the other end fastened to the bottom of the bag, a plurality of beads mounted upon said cord and 20 retaining stops therefor.

3. In a cleaning device the combination of a closure of suitable material, a bag of fabric depending from said closure, a cord lying within said bag and having one end secured 25 to the closure and its other end secured to the bottom of the bag, and a plurality of beads loosely mounted upon said cord and means retaining said beads within certain limits.

WILLIAM H. CALLAHAN.
